HATCHWAY TABLE

Malcolm Maclaggart, Welwyn, England

Application March 7, 1945, Serial No. 581,502
In Great Britain January 27, 1944Section 1, Public Law 690, August 8, 1946
Patent expires January 27, 1964

4 Claims. (Cl. 311—18)

1

This invention relates to improvements in or relating to domestic furniture and particularly tables, e. g. dining tables.

The term "table" as used herein is intended to cover any device having a horizontal or substantially horizontal upper surface suitable for supporting various articles, provisions and so on, e. g. a device in the nature of a table-top, counter, trolley, shelf, sideboard or the like or a part which in cooperation with other parts forms such a device.

According to the present invention there is provided a frame adapted to form a hatchway in a wall, partition or the like and a platform or the like located in said frame and adapted to be moved at will into positions forming a table on either side of said frame.

The aforesaid platform or the like may also be adapted to move from a horizontal position into a position lying in the plane of the hatchway so enabling it to be disposed within the compass of the hatchway when no table is required on either side thereof.

Any desired foldable or slidable brackets, bearers, legs or the like may be provided for supporting the aforesaid platform or the like when it is in either of its table-forming positions. Thus for instance bracket members may be hingedly mounted on the frame and be adapted to swing from positions in which they rest flush with the faces of the hatchway into positions in which they extend horizontally from the hatchway.

The aforesaid frame is preferably of a size adapted to form a hatchway of dimensions similar to those of hatchways frequently provided between kitchens and dining rooms and in such cases and assuming that the platform or the like is of dimensions appropriate for being nested wholly within the limits of the hatchway such table would be of unduly small size for instance for use as a dining table. In such cases and in other circumstances where a larger table than that afforded by the said platform or the like is required the said platform may be formed in two or more parts adapted to be superimposed when moved to their closed positions and to lie in a single plane when extended into their horizontal positions and in such cases only that part of the platform or the like which is adjacent to the hatchway may be adapted to be moved to both sides of such hatchway. In other arrangements for providing a table of greater area than that of the said platform or the like one or more subsidiary platforms may be slidably disposed with

2

respect to the main platform so as to form an extendible leaf on one or more of the sides thereof or one or more subsidiary platforms may be carried by the above mentioned frame, said subsidiary platform or each of said subsidiary platforms in the latter arrangement being adapted to be moved from a position in which it lies vertically within the compass of the hatchway into a position in which it lies in the plane occupied by the main platform or the like when the latter is in its horizontal position, said subsidiary platform or platforms thus forming side extensions of the main platform.

It is also within the scope of the present invention to provide two or more combined table and hatchway units in side by side relationship so that the platforms or the main platforms of the respective units when in their horizontal positions form a continuous table top. In the latter event one or more of the units may include subsidiary platforms of the above mentioned kind adapted to extend to one or both sides of the main platform or platforms, the main platforms being spaced apart by appropriate distances where necessary, and/or such unit or units may include a platform or platforms of the above mentioned kind comprising a plurality of parts.

A combined hatchway and table in accordance with the present invention may include any desired shutter or shutters, e. g. of the roller-blind or roll-top desk kind, for closing the opening which is formed in the hatchway when the table-forming elements are in their opened conditions and/or for totally enclosing such elements when they are in their closed positions although in some cases the table elements themselves may, when closed, form a closure for the hatchway.

A device according to the present invention offers numerous advantages as compared with an ordinary table in that when the table is not required for use it can be nested in the hatchway and in that condition it does not occupy any floor space in the room or rooms concerned. Such device also offers great advantages as compared with the normal hatchway in that the amount of work involved in moving articles, provisions and so on from one room to a table in another room and vice versa is greatly reduced. Thus in the use of the normal hatchway such articles, provisions and so on have to be passed through the hatchway either individually or on a tray and then carried to the table and during the reverse process such articles, provisions and so on have to be moved from the table and passed back through the hatchway or collected from the table

onto a tray and then passed through the hatchway. With the aid of the present device however the said articles, provisions and so on can be placed on the platform or the like or that part thereof which is adapted for being moved into either room at will and mere movement of said platform or part into a position projecting into the other room effects the desired transference to such other room and automatically forms a table.

In order that the present invention may be well understood I will now describe, by way of examples only, some embodiments thereof with reference to the accompanying drawings, in which—

Figure 1 is a diagrammatic perspective view of one form of the device with all of the parts, with the exception of one bracket, in their fully closed positions.

Figure 2 is a diagrammatic perspective view of the device shown in Figure 1 with some of the parts in their fully opened condition.

Figure 3 is a diagrammatic view of the same device with all of the parts in their fully opened positions.

Figure 4 is a diagrammatic perspective view showing the same device with the parts in their opened positions and forming a dining or like table.

Figure 5 is a diagrammatic perspective view of a modified device showing some parts of the device in their closed positions and some parts in their opened positions.

Figure 6 is a diagrammatic perspective view of another form of device in its fully closed position.

Figure 7 is a diagrammatic perspective view of the device shown in Figure 6 with the parts in a partially opened condition.

Figure 8 is a diagrammatic perspective view of the device shown in Figures 6 and 7 but with all of the parts in their fully opened positions and.

Figure 9 is a diagrammatic perspective view of the same device but with the parts in their positions forming a dining table.

Referring to Figures 1 to 4, the device comprises a rectangular frame 1 made from wood, metal or other suitable material adapted to be placed in an opening in a wall, partition or the like dividing a dining room from a kitchen, such opening measuring say about two feet horizontally and two feet vertically and being positioned so that its base is slightly below the height of a normal dining table.

The frame 1 is preferably of such a width that its front and back surface lie flush with the wall, partition or the like in which it is inserted, the surface presented forwardly in the figures facing the dining room and the opposite surface facing the kitchen.

The top member of the frame 1 lines the top of the opening in the wall, partition or the like and forms a box in which is mounted a roller blind 2, said blind when drawn downwardly entirely covering the opening formed by the frame.

The sides of the frame 1 line the sides of the opening in the wall, partition or the like and their inner surfaces are provided with runways for the roller blind 2.

The bottom member of the frame lines the base of the opening in the wall, partition or the like, such member being wider than the side members, the face presented towards the dining room being if required, wider than that presented

towards the kitchen so as to form a flange to assist in fixing.

Two bracket arms 3, 3 are pivotally mounted on the frame 1 for movement into the positions shown in the figures, i. e. projecting at right angles into the kitchen, and into positions in which they are superimposed and lie flush with the adjacent face of the frame, said bracket arms being disposed at the base of the frame and being of lengths approximately equal to the width of the opening in the frame.

Two bracket arms 4, 4 are similarly mounted and disposed on the side of the frame opposite to that on which the bracket arms 3, 3 are located, i. e. the arms 4, 4 can be swung into positions in which they extend at right angles into the dining room (both arms being shown in that position in Figures 3 and 4 and one of such arms being shown in that position in Figure 2) and into positions in which they are nested and superimposed flush with the frame, both arms being shown in the latter position in Figure 1.

The upper surfaces of the bracket arms 3, 3, 4, 4 and the upper surfaces of the base member of the frame 1 lie in the same horizontal plane and the opposed arms lie in straight lines, i. e. at right angles to the frame, when fully opened. The said upper surfaces form a bearing surface for a platform 5, such platform being of rectangular form, one dimension of which corresponds to the width of the opening in the frame 1 and the other dimension of which corresponds to the length of the above mentioned bracket arms. The said platform is slideable from a position in which it projects wholly to one or the other side of the frame 1, i. e. into the position shown in Figures 1, 2 and 3 in which it projects wholly into the kitchen and into the position shown in Figure 4 in which it projects wholly into the dining room. If desired the undersurface of the said platform may be provided with ball or roller bearings and grooves or channels may be formed in the upper surfaces of the bracket arms and across the base member of the frame 1 for forming tracks for such ball or roller bearings.

Those parts of the device which have so far been described provide a table which can be extended through the opened hatchway into the dining room when required and passed into the kitchen when it is not required in the dining room, and in the latter circumstance the bracket arms 4, 4 can be closed so leaving the dining room wall free from any projections. The transference of articles, provisions and so on from the kitchen to the dining room and vice versa can be very easily effected, and, for the purpose of such transference, there is no necessity to move such articles, provisions and so on from or to the table. Moreover the blind 2 enables the hatchway to be completely closed when the parts are in the position for forming a table in the dining room. The table area is however limited to that of the platform 5 and whilst this may be appropriate for forming a table top suitable for accommodating three persons around its three free sides an increase in the size of the platform 5 to an extent appropriate for forming a table say for five persons would probably result in the hatchway being objectionably wide. The construction shown in Figures 1 to 4 includes one example of suitable means for providing a larger table without increasing the size of the slideable platform, such means comprising subsidiary flaps 6, 6 hingedly connected to the bracket arms 4, 4,

said flaps being adapted to be swung at will either into vertical planes, i. e. into positions in which they are coplanar with the brackets to which they are connected and can therefore be nested within the compass of the frame 1 when the brackets are moved to their closed positions, or into horizontal positions in which, assuming the arms 4, 4 are in their opened positions, side extensions are formed for the platform 5 as indicated in Figure 4.

In order to support the above-mentioned flaps in their horizontal positions subsidiary bracket arms 7, 7 are pivoted to the arms 4, 4 or to the frame 1, the said arms 7, 7 being adapted to nest with the arms 4, 4 within the compass of the frame 1, the arms 4, 4 being for instance provided with recesses for receiving the arms 7, 7.

In a modification of the construction shown in Figures 1 to 4 instead of providing a hinged flap on both sides of the slidable platform 5 a hinged flap may be provided on only one side thereof.

In a further modification of the arrangement shown in Figures 1 to 4, instead of providing one or more hinged flaps for providing a table of greater area than that of the sliding platform 5, I may provide a composite slidable platform comprising two or more sections adapted to be superimposed when it is desired to pass the platform through the hatchway and to be extended so as to lie in a common horizontal plane when such composite platform is fully extended to one or to either side of the hatchway. In such arrangement the various sections may be hingedly interconnected or they may be slidably interconnected, e. g. in a manner similar to that already used in extending tables.

The arrangement shown in Figure 5 is similar to that shown in the earlier figures subject to the side flaps and bracket arms when closed being nested in the frame in side by side instead of superimposed positions and similar reference numerals are accordingly employed for designating corresponding parts.

The arrangement shown in Figures 6 to 9 provides a table which is extendible from the hatchway into a dining room to an extent greater than that to which the slidable platform itself extends, it being possible in this manner to form a table of which the longer dimension extends at right angles to the wall in which the hatchway is formed. In this construction the device includes a frame 9 which is very similar to the above described frame 1 in that it is rectangular and its top member constitutes a housing for a roller blind 10 which can be drawn downwardly to close the hatchway when the table forming parts are in their extended positions. Such table forming parts comprise a section 11 pivotally mounted on arms 12, 12 and a slidable platform 13. The said arms 12, 12 are pivotally mounted at the base of the frame 9 and adapted to be swung in vertical planes into positions in which they nest in the frame 9 and into positions in which they project horizontally into the dining room, any suitable legs, e. g. legs 15 pivotally mounted on the section 11, being provided for supporting said section in its horizontal position.

The pivotal axis of the section 11 is parallel to the pivotal axis of the arms 12, 12 and the pivotal connection between such parts is such that when extended into horizontal positions (i. e. the positions shown in Figures 8 and 9) the upper surfaces of the section 11 and arms 12 respectively lie in the same horizontal plane, and when the arms 12 are upturned into vertical positions and

the section 11 is downturned into a vertical position said arms and section become superimposed and nested within the compass of the frame 9.

The inner faces of the arms 12 and the edges 5 of the platform 13 are rebated as shown in Figure 8 so that the slidable platform can be appropriately supported and guided by said arms.

On the kitchen side of the hatchway shown in Figures 6 to 9 there is provided a slideway for 10 receiving the slidable platform 13, such slideway being formed for instance in a shelf, table, brackets or the like, part of a suitable slideway being indicated in Figure 8 and designated 14.

When it is desired to transfer articles, provisions and so on from a kitchen to a dining room 15 table with the aid of the device shown in Figures 6 to 9 the said articles, provisions and so on are located on the platform 13 whilst the latter is in a position extending into the kitchen, the section 11 is swung outwardly and downwardly into the position shown in Figures 8 and 9 and the legs 15 are opened into the positions shown so forming a part of the table, and the slidable platform 13 is then moved through the hatchway into the position shown in Figure 9, i. e. into a position in which it abuts against the section 11 and completes the formation of the table. The shutter 10 is then drawn, completely separating the dining room from the kitchen. When it is desired to carry out the reverse process the articles, provisions and so on to be returned to the kitchen 20 are assembled on the platform 13, the blind 10 is raised, the platform is moved through the hatchway and after folding the legs 15 the section 11 is moved from the position shown in Figures 8 and 9 through the position shown in Figure 7 into the position shown in Figure 6.

Whilst I have hereinbefore described some embodiments of the present invention I wish it to be understood that there may be various modifications without departing from the scope of such invention. Thus for instance the slidable platform or the like may be associated with any desired number of slidable or hinged flaps and the slidable platform may itself be adapted to be nested within the compass of the hatchway, e. g. the platform 5 shown in Figures 1 to 4 may be turned from the position shown in Figures 1 to 3 into a vertical position within the frame 1.

I claim:

1. An article of furniture comprising a frame forming a hatchway, a platform located in said hatchway and slidable in a horizontal plane from a position projecting from one side of said frame into a position projecting from the other side thereof, supporting brackets located on at least one side of said frame and movable from positions in which they are nested in said frame into positions in which they extend horizontally therefrom, and a panel carried by said brackets and spaced from the said frame by a distance appropriate for receiving the said platform when the latter is in a position projecting from the said side of the frame.

2. An article of furniture according to claim 1 wherein the said panel is pivotally mounted on the said supporting brackets and said supporting brackets are pivotally connected to the frame, said brackets being swingable into horizontally extending positions and into vertically extending positions nested in the said frame and the said panel being swingable into a position superimposed on said supporting brackets and nested in said frame and into a position extending horizontally therefrom.

3. An article of furniture comprising a frame forming a hatchway, a platform located in said frame and slidable in a horizontal plane from a position located on one side of said frame into a position located on the other side of said frame, supporting brackets disposed on at least one side of said frame and movable from positions lying in the plane of the frame into positions projecting at right angles therefrom, provision for moving said platform at will into a horizontal position or into a vertical position nested in said frame, and a shutter for closing the hatchway formed by said frame when the platform is horizontally disposed.

4. An article of furniture comprising a frame forming a hatchway, a platform slidably located in said frame and movable at will into positions forming a table on either side of said frame and supporting members pivotally mounted on said frame at their inner ends and connected at their outer ends by a member with a flat surface, said supporting members being movable from a position in which they are nested in said frame into a position in which they project therefrom and form both a support for and a surface horizontally continuous with the said platform when the latter is in one of its projecting positions.

MALCOLM MACTAGGART.
